SPRAYER CONSTRUCTION

George H. Palm, Chicago, Ill.

Application July 17, 1952, Serial No. 299,335

19 Claims. (Cl. 299—89)

This invention relates to a spray gun construction, and particularly that of a sprayer head construction for use with a container having liquid to be sprayed and/or foamed and sprayed.

Among its objects is the provision of means so that the spray gun may be used to spray paints, varnishes, lacquers, disinfectants, and other liquids, and when used with an attachment for foaming liquids, provides means for spraying a foamy cleaning compound or detergent upon carpets, rugs, furniture, and other articles that are to be cleaned.

Another object of the invention is to provide a simple sprayer head construction wherein the cost of manufacture is reduced and, at the same time, to provide an improved appearance.

Still another object of the invention is to provide a sprayer head construction which eliminates soldering, and provides a sprayer head which may be assembled using a minimum number of parts which may be either press formed or produced from simple structural shapes of convenient lengths.

Another object of the invention is to provide a sprayer head construction wherein the parts thereof may use materials other than the conventional brass and copper usually used.

Still another object of the invention is to provide a sprayer head construction which may be fabricated from simple stampings, and shipped in a knocked-down condition for later reassembly by the purchaser or distributor, and is particularly adapted by a detachable hose adapter construction for the interchange of the hose adapter when used with different types of vacuum cleaners where in the wands or hose ends of different makes of vacuum cleaners are of different sizes and shapes.

Another object of the invention is to provide a hose adapter for a sprayer head construction which has the end thereof flexible for attaching to a wand or hose end of a vacuum cleaner hose, permitting the attachment of various types of vacuum cleaner hose ends.

Another object of the invention is to provide a coupling construction for the attachment and detachment of different shaped hose ends.

Another object of the invention is to provide a cover construction for a sprayer head which permits the sprayer head to be attached either to a conventional glass jar used in spraying, or to a metal can containing the fluid to be sprayed.

Another object of the invention is to provide novel means for mounting the valve mechanism and spray tube to simplify the manufacture and reduce the cost of the sprayer head construction.

A further object of the invention is to provide simple means for detachably securing the hose adapter to the sprayer head, which also serves to assemble the support for the valve mechanism on the sprayer head.

Another object is the provision of a removable and replaceable attachment for a sprayer head whereby, when in place, a foaming cleaning compound may be

2

sprayed, and when detached, the sprayer head is adapted for the spraying of liquids.

A further object is to provide a spray gun having a minimum number of parts, and which is simple in construction and operation.

Many other objects and advantages of the construction herein shown and described will be obvious to those skilled in the art from the disclosure herein given.

To this end, my invention consists in the novel construction, arrangement, and combination of parts herein shown and described, and more particularly pointed out in the claims.

In the drawings, wherein like reference characters represent like or corresponding parts:

Fig. 1 is a preferred form of sprayer head, partly in section, illustrating the sprayer head attached to a conventional form of metal can, but which is also adapted for attachment to the conventional glass jar used in liquid spraying;

Fig. 2 is a view taken approximately along line 2—2 looking in the direction of the arrows, partly in section, illustrating the bottom of the sprayer head of Fig. 1;

Fig. 3 is a modified form of a coupling construction similar to that of Fig. 1 to provide an adjustable form of coupling to connect different vacuum cleaner hose ends to the hose adapter of the spray gun;

Fig. 4 illustrates a modified form of sprayer head for a spray gun, and shows modifications of the tube mounting, valve stem construction, and securing means for the hose adapter from that of Fig. 1;

Fig. 5 is a view taken substantially along line 5—5 of Fig. 4, partly in section, illustrating the modified tube support construction and valve stem construction;

Fig. 6 is a view taken along line 6—6 of Fig. 4, partly in cross section, illustrating in elevation the construction of the tube support;

Fig. 7 is a view, partly in cross section, illustrating a modified form from that of Figs. 1 and 4 of the securing means for the hose adapter, and which is also adapted for use as the push-button or thumb nut of the valve mechanism; and

Fig. 8 is a view, partly in section, of a modified form of foaming attachment from that of Fig. 4, and illustrates the removal of the screens.

Referring to the drawings, particularly Figs. 1 and 2, a sprayer attachment 10 for use for either spraying liquids, or when a foaming attachment 11 is provided, for foaming and spraying cleaning solutions or detergents, is shown. In this form, a sprayer head 12 is shown as being detachably connected to a metal container 13 having a narrow-necked opening 14 to which the sprayer head is detachably connected by a complementally formed, threaded cap 15 which is similar to the conventional cap of the container. The container is adaptable either for holding paint, insect spray, varnish, cleaning solution, etc., which may come in the container as a particular product, or it may be a separate container sold with the spray gun, and which may be filled with the liquid which is to be sprayed or foamed. Although it is preferred to use a metal container of this form because it is inexpensive to manufacture and unbreakable, the sprayer head of this embodiment is adapted by means of the depending cap 16 for use either with a glass container

or with the metal container; and when used with a glass container, the cap for the metal container is positioned within the glass container and out of the way. The cap 16 may be provided with a threaded construction complementary to the thread 16' of the glass jar illustrated in Fig. 4, and the thread on the cap 16 may be either roll-threaded in place, or may be formed by indenting in three equally spaced indentations 17, 17' and 17'' to form

70

a modified thread wherein the pitch of the thread on the cap compares to the rise of the indentations axially along the cap, and it is necessary that the indentation 17' (Fig. 5), which permits the cap to be positioned on the jar, shall be formed at the edge of the cap.

The sprayer head 12 is preferably formed with an upper cylindrical portion 18, and a lower cylindrical portion forming the threaded cap 16. Although it is preferred to form the sprayer head from steel, it may be suitably formed from brass, copper, or aluminum. The design of the sprayer head also permits it to be molded from a suitable plastic or die cast. It is preferred to bright zinc plate the steel sprayer head, and then chrome dip to preserve the zinc plating. A disk or partition 19 is formed from thin gauge metal, such as aluminum or other suitable metal, and is formed with diametrically spaced lugs 20 which are adapted to extend through openings 21 in the intermediate flange between the upper cylindrical portion 18 and the cap 16. When assembled in position, the lugs may be staked to secure the partition in place.

The sprayer head 12 is provided with an outlet opening 22 and an inlet opening 23 diametrically opposite, which may be either punched or suitably drilled to the required size. The opening 22 receives the tapered ferrule 24 of the foaming attachment 11. The tapered ferrule permits the foaming attachment to be readily adapted for existing sprayer heads formed with a similar opening and tube to that now in use. The ferrule 24 is provided with an opening 25 which extends about the end of the liquid spray tube 26, as shown in Fig. 1, to provide an annular passage 27 for the discharge of the air from the source of air to which the spray gun is attached, such as from a vacuum cleaner.

The tube 26 extends downwardly into the container 13, as shown, and is affixed in position on the sprayer head by a tube support 28, which extends through complementally formed openings 29 in the caps 15 and 16. In assembling the caps 15 and 16 together, they are mounted on the ferrule or tube support 28, and the free end of the tube support is staked over, as at 30, affixing the caps together. The tube is affixed in place, as shown in Figs. 1 and 2, by deforming the tube support 28 from a cylindrically shaped member to a square-shaped portion, shown at 31, causing the tube to be complementally deformed at 32 to a similar square-shaped cross section. Removal of the tube is thus prevented, and the tube is rigidly affixed and aligned in position upon the sprayer head 12 with the upper end of the tube in axial alignment with the opening 22.

Each of the caps 15 and 16 is provided with an opening 33 to receive the valve rod 34 of the valve mechanism 35. The opening 33 is shaped as illustrated in Fig. 2 to receive the flattened portion 36, which serves to guide the rod during its vertical movement, and the rounded portion of the opening permits the entry of the threaded end 37 of the rod for mounting the thumb control nut or button 38. The lower end of the valve rod 34 is provided with a U-shaped end 39 over which a brass valve 40 is affixed in axial alignment with the lower end of the tube 26 for the control of the liquid under pressure through the tube. The upper end of the valve rod extends through a compression spring 41, and is detachably affixed to the lower end of the thumb nut by the turned boss 42 shaped as shown in Fig. 1. The upper end of the thumb nut 38 may be formed with a head 42' and, as shown, knurled, and it is preferred to form the thumb nut from round stock to the shape shown to extend through a complementally formed opening 43 in the sprayer head. In assembling the valve mechanism on the sprayer head, the valve 40 is first affixed to the valve rod 34, and the upper end of the valve rod is inserted through the opening 33, and with the valve inserted in the tube end, the thumb nut is assembled in position on the threaded end 37 after the spring has

been first affixed to the end 42 of the thumb nut. The thumb nut is then adjusted on the valve rod to permit the valve to be adjusted with respect to the tube end for adjusting the flow of liquid under pressure through the tube. The amount of liquid sprayed may be adjusted by adjusting the thumb nut.

The valve 40 is preferably formed from rod stock, and is provided with a conical seat 44 and a tapered end 45. In the closed position, as shown in Fig. 1, the valve 44 seats against the end of the tube, and in the open position, the adjustment of the tapered end 45 within the tube, as controlled by the push button 42, determines the amount of liquid discharged from the spray gun. The valve 40 is provided with a hole 46 complementary to the upturned end of the valve stem, and is affixed in place by pressing the valve on to the rod and, if necessary, may be staked in place.

Referring to Figs. 1, 2, and 3, there is illustrated a hose adapter 47 which is formed separately and detachably mounted within the opening 23 of the sprayer head. Securing means 48, preferably formed from rod stock in a screw machine, is inserted through complementally formed openings 49 in the sprayer head and hose adapter at the upper end. At the lower end, the securing means is formed with a threaded stud 50, which extends through an opening 51 in the hose adapter, and is threaded into a ferrule 52 staked in position after mounting in complementally formed openings 53 in the caps 15 and 16. The ferrules 52 and 28 serve to affix the cap and disk 19 together, and when attached to the securing means 48 affix the partition 19 to the sprayer head. The lugs 20 may or may not be staked over, and when not staked, permit ease in the disassembly of the disk from the sprayer head for replacement and re-pair, if necessary.

The outer end of the hose adapter is preferably formed with a tapered end 54, or it may be formed as a straight section 54', as shown in the dotted lines, and is particularly bent in the manner shown to provide a hand grip for the spray gun. In order to detachably connect the hose adapter 47 to a wand or hose end 55 of a vacuum cleaner hose, a tube 56 of plastic, or other suitable material, is cemented or clamped to the tube at the upper end 57, and the tube at the free end is provided with a plastic ring 58 to which the tube is integrally molded. The ring 58 permits the tube to be rolled back upon itself to the dotted position 56', whereupon the hose end 55 is placed in position overlying the tapered end of the hose adapter, and the tubing rolled back to the solid line position, as shown, is of such size that there is a frictional fit between the hose end and the tube, and there is also enough stretch provided that different sizes and shapes of hose ends may be attached to the hose adapter. The friction is also such that the weight of the hose may be supported in the spraying operation. The same connection is also provided if the hose adapter is formed from straight tubing, as shown in the dotted position 54'. A hand grip is provided in the extended position of the tubing, and in this manner, the hand grip, when held by the operator, also provides a clamp between the ends of the adapter and hose end and the tubing.

Fig. 3 illustrates another embodiment of the coupling formed by the plastic tubing 56a, wherein the tubing is formed with a garter-type coiled spring 59 attached by turning over the end of the hose and seam welding it in position. The tubing 56a may be rolled back into the dotted position 56b in order to couple the free end of the adapter 47 and the hose end 55' together, as described above. The coiled spring 59 provides additional frictional grip, if necessary, for supporting the hose in spraying.

Although each of the embodiments of the coupling has been particularly described with reference to coupling a hose end and hose adapter of a spray gun together and

providing a sealed joint, the coupling is equally adapted for sealing the joints between the wands, and also between a wand and hose end, and to provide sufficient friction in a joint of this nature to prevent its uncoupling.

In use, the container 13 is filled with the liquid to be sprayed or foamed and sprayed, and the hose connection is connected to a source of air under pressure by the hose adapter 47 and the coupling member 56. The user may grasp the coupling member 56, and upon depressing the push button 42, the valve 40 is unseated, permitting the contents of the jar or container to be forced through the tube 26 as the contents of the container 13 are placed, under the pressure of air within the hose, through the enlarged opening between the flattened portion 36 of the valve rod 34 and the hole 33. The air discharged through the spraying head from the hose adapter breaks up the liquid into minute particles, and sprays them upon the article to be sprayed as the air and liquid are discharged through the opening 22. Upon release of the push button 42, the spring 41 biases the valve to its closed position, and the discharge of the sprayed liquid ceases.

In this same form, as illustrated in Fig. 1, when the foam sprayer 11 is in position, as illustrated in greater detail in Fig. 4, the spray gun is adapted for foaming and spraying the liquid as it is discharged from the container. The foam sprayer attachment comprises the ferrule 24 which is tapered to fit the opening 22, and the center opening 25 provides an annular passage 27 for the discharge of the air under pressure from the vacuum cleaner, or other source of air pressure. The ferrule is staked in position in a cup-shaped member 60, the outer end of which is provided with an annular recess 61 in which is positioned a series of foraminous disks or screens 62. The disks are so shaped that they may be sprung into and out of position in the annular groove when it is desired to clean from the disks any dirt or dried residue left by the foamed liquid after using the foam sprayer attachment. When it is desired to use the spray gun simply as a liquid sprayer, the foam spray attachment 11 is readily detached, and may be attached through the frictional fit of the tapered end of the ferrule 24 and the opening 22. The construction of the foam sprayer attachment may be from any suitable material which is readily drawn, and which does not corrode in use. Similarly, the disks or screens may be formed from any suitable non-corrosive metal or plastic material which has sufficient resiliency to be readily attached and detached to the open end of the cup-shaped member 60 forming the foam spray attachment.

If desired, for certain detergent liquids to improve the foaming thereof, the foraminated disks or screens may be provided with preferably three, triangularly spaced dimples 62', Fig. 4, which permit nesting of the disks, as shown, or rearrangement to permit spacing of one or more of the disks, as desired. It is to be understood that other means will suggest itself to those skilled in the art for permitting either nesting or spacing of the foraminated disks. It is also within the scope of the invention that the foraminated disks may be used nested together without means for spacing them apart.

Referring to Figs. 4, 5, and 6, there is illustrated another embodiment of the spray head which is adapted either for the spraying of liquid, or the foaming and spraying of liquid, as the modification illustrated in Fig. 1. In this embodiment, similar or primed reference characters will indicate like or similar parts. The liquid tube 26' is supported in position by a tube support 63 formed as illustrated in Figs. 4 and 6, and extends through the modified partition plate 19' and the upper end of the spray head 12' through an opening therein, wherein it is staked over as at 64. The tube extends through the holes 65 and 66 in alignment with the opening 22 at the upper end of the tube and with a hole 67 in the partition plate 19'. The valve rod 34' is similarly constructed as the embodiment of Fig. 1, but is modified therefrom in that

the flattened end 36' is threaded at its upper end for mounting in the thumb nut 38', which has a threaded opening 68 complementary to the thread of the valve rod 34'. The thumb nut 38 is preferably formed from hexagonal stock, and extends through a complementary formed hexagonal or circular opening 69 in the sprayer head. A spring 41' normally biases the valve 40 to its closed position.

A hose adapter 47' is provided with a tubular end 70 to extend through the opening 23 and with an enlarged end 71 which is adapted to fit a wand or hose 55 of a vacuum cleaner hose to which the spray gun is attached. In this embodiment, the hose adapter may be interchanged with other hose adapters so that the preferred free-end 71 may be selected which fits the form of hose end or wand 55 of any particular type of vacuum cleaner. It is customary in the vacuum cleaner art for each manufacturer to provide a wand or hose end different from other manufacturers to prevent the interchange of cleaning tools. Previously this has required the fabrication of a different form of sprayer head for each make of cleaner. It is thus evident that by the present embodiment, it is possible to fabricate a common sprayer head requiring only the interchange of the hose adapter 47' to provide each manufacturer with a spray gun at reduced cost because of the simple construction.

Although it is possible to affix the hose adapter in the same manner as described with respect to the hose adapter of Fig. 1, a construction has been provided which further reduced the cost of the construction by deforming the partition 19' in the manner illustrated at 72 to provide a threaded opening 73 for the reception of a common bolt 74 which extends through the threaded openings 73 at the lower end, and at the upper end through an opening 49' in the sprayer head. In order to reinforce the tubular end 70, a bushing 75 is placed between diametrically opposite lugs 76 formed by deforming the tube as shown. In assembling the different adapters in place, the adapter is inserted into the opening 23, and the bolt 74 is threaded in position. The bolt 74 also serves, along with the tube support 63, to affix the partition plate 19' in position. In use, the cap 16 of the sprayer head 12' is threaded in position on a glass jar 13' after a gasket 77 has been placed within the cap 16 to seal the liquid within the container. In the modification of Fig. 1, a similar gasket 77 is used if the spray head of this embodiment is affixed to a glass jar 13', and if it is used with a metal container 13, a gasket 77' is inserted in the cap 15. In the embodiment of Fig. 1, the cap 15 permits the metal container to be supported by the cap and the can to be sealed against the gasket 77 of the cap 16 as the can is assembled in the sprayer head 12.

The operation of the embodiment of the sprayer head of Fig. 4 is similar to that described with respect to the embodiment of Fig. 1, with the exception that air pressure is applied to the liquid through an opening 78 in the partition 19', rather than through the enlarged opening formed between the flattened portion 36 and the opening 33 for the valve rod 34. The control of the flow of fluid is adjusted in the same manner by adjusting the tension of the spring 41 by the thumb nut 38'. However, the thumb nut may provide an additional function in this embodiment in that, when the spray gun is not being used but connected to a source of air under pressure, the air is discharged through the opening 22, and through the opening 68 provided in the thumb nut. The liquid in the container is placed under full pressure of the source of air by placing the thumb over the opening in the thumb nut so that full air pressure is applied to the top of the liquid through the opening 77. The amount of liquid sprayed or foamed is then controlled by the amount that the valve 40 is opened. Normally, the spray gun is used with a slight amount of air bled to the atmosphere through the opening 68.

Referring to Fig. 7, there is illustrated a modification of the securing means for a hose adapter 47a. The hose

adapter is similarly constructed as the embodiment of Fig. 4 with the exception that the holes 49a are punched to receive the hexagonal securing means 48a. The securing means is threaded as illustrated to receive a machine screw 79. The securing means 48a is also provided with a counterbore 80, similar to that of the embodiment of Fig. 4, to receive the spring 41' when the securing means 48a is used as an embodiment of the thumb button 38'. When the sprayer head is constructed using the embodiment of the securing means of Fig. 7, it is evident that the cost of the sprayer head is reduced still further by the simplification of the reduction in the number of different parts.

Referring to Fig. 8, there is illustrated a modified foaming attachment 11'. It is similarly constructed as that illustrated with the spray gun of Fig. 4. Therefore, the like or similar reference characters will indicate similar parts, and only the modified construction for the mounting of the foraminated disks 62a and 62b need be additionally described. The cup-shaped member 60' is preferably drawn with an enlarged opening 81 slightly tapered and large enough to permit entry of the alternate screen disks 62a and 62b, preferably four in number. An annular groove 82 is spun in the opening 81, which forms a stop to prevent the disks from falling out, but permitting the flexible disks to enter easily into the annular groove 61'. The foraminated disks 62b may be either formed with the triangular spaced dimples as Fig. 4, or as shown with an annular raised portion 83 on one side and a dimple 84 on the opposite side to properly space or nest the foraminated disk. The disks may be otherwise rearranged, depending upon the liquid to be foamed.

When it is desired to remove the foraminated disks in either of the embodiments of Figs. 4 or 8 for cleaning, the knurled securing means 48 is removed and inserted through the opening 25. The length of the securing means 48 is such that the disks may be pushed outwardly, bending the disks so that they are readily detached from the annular groove 61 or 61' of each of the foaming attachments. The cleaned disks are replaced by snapping them back in position, and the securing means 48 is replaced on the sprayer head. The machine bolt or screw 74 of the embodiment of Fig. 4 is of such a length that it may be similarly used to detach the foraminated disks or screens from the foaming attachment. The length and cross section of the securing means 48a of the embodiment of Fig. 7 may be similarly formed to remove the disks. From the above, a simple arrangement which is always at hand may be used to remove the disks for cleaning, although other suitable means are equally adaptable.

When using the embodiments of Figs. 1 and 2 as a foam sprayer attachment, either of the containers 13 or 13' is filled with a suitable liquid cleaning compound or detergent, and air is admitted to the sprayer head. By depressing the push button, the valve is unseated, permitting air under pressure to discharge the cleaning compound through the tube and into the foam sprayer attachment, where the liquid and the air discharged through the sprayer head encounters the several foraminated disks in the foam sprayer shell 60, and is blown through the perforations thereof. This causes the liquid to be agitated and broken down into a foaming condition either by the spaced, foraminated disks, or contiguously mounted disks. As the liquid is discharged as foam, the air pressure also serves to spray the foamed liquid upon the surface to be cleaned.

Any suitable liquid cleaning compound which can be broken down into a foamed condition may be used. The compound may comprise a soapy solution, or it may be composed of chemicals such as are used in the "foam" method of cleaning. A spray gun equipped with the above described attachment may be used to spray a clean-

ing compound foam upon carpets, rugs, upholstery, and many other objects.

Having thus described my invention, it is obvious that various immaterial modifications may be made in the same without departing from the spirit of my invention; hence, I do not wish to be understood as limiting myself to the exact form, construction, arrangement, and combination of parts herein shown and described, or uses mentioned.

What I claim as new and desire to secure by Letters Patent is:

1. In a spray gun including a liquid container for the liquid to be sprayed and a hose connection, a sprayer head comprising a sprayer cover for the liquid container comprising an upper cylindrical portion provided with a discharge outlet opening and an inlet opening for a spraying fluid under pressure for detachably mounting the hose connection, a lower cylindrical portion including securing means complementally formed to the threaded end of the container for detachably mounting and securing the sprayer head on the container, and an intermediate wall detachably mounted intermediate the ends of the sprayer head forming a chamber for the discharge of the fluid under pressure from the inlet opening to the outlet opening, said hose connection being detachable, and securing means for detachably securing the hose connection within the inlet opening and to the intermediate wall and the intermediate wall to the sprayer cover.

2. In a foam spray gun adapted for detachably securing to different hose couplings and including a liquid container for the liquid to be foamed and sprayed and a hose connection, a sprayer head comprising a sprayer cover for the liquid container comprising an upper portion provided with a discharge opening and an inlet opening for a spraying fluid under pressure for detachably mounting the hose connection, a lower portion including securing means complementally formed to the threaded end of the container for detachably mounting and securing the sprayer head on the container, an intermediate wall detachably mounted intermediate the ends of the sprayer head forming a chamber for the discharge of the fluid under pressure from the inlet opening to the discharge opening, a foam sprayer attachment detachably mounted in the discharge opening, the hose connection detachably secured in the inlet opening, securing means for detachably securing the hose connection within the inlet opening and to the intermediate wall and the intermediate wall to the sprayer cover, whereby the sprayer head is adapted for either spraying or foaming and spraying a liquid, and the sprayer head is further adapted for coupling to hoses having different end coupling by changing the hose connection.

3. In a spray gun including a liquid container for the liquid to be sprayed and a hose connection, a sprayer head comprising a sprayer cover for the liquid container comprising an upper portion provided with a discharge outlet opening and an inlet opening for a spraying fluid under pressure for detachably mounting the hose connection, a lower portion including securing means complementally formed to the threaded end of the container for detachably mounting and securing the sprayer head on the container, and an intermediate wall detachably mounted intermediate the ends of the sprayer head forming a chamber for the discharge of the fluid under pressure from the inlet opening to the outlet opening, said hose connection being detachable, and securing means for detachably securing the hose connection within the inlet opening and to the intermediate wall and the intermediate wall to the lower portion of the sprayer head.

4. In a spray gun including a liquid container for the liquid to be sprayed and a hose connection, a sprayer head comprising a sprayer cover for the liquid container comprising an upper cylinder portion provided with a discharge outlet opening and an inlet opening for a spraying fluid under pressure for detachably mounting the

hose connection, a lower cylindrical portion including securing means complementally formed to the threaded end of the container for detachably mounting and securing the sprayer head on the container, an intermediate wall detachably mounted intermediate the ends of the sprayer head forming a chamber for the discharge of the fluid under pressure from the inlet opening to the outlet opening, said hose connection being detachable, securing means for detachably securing the hose connection within the inlet opening and to the intermediate wall and the intermediate wall to the sprayer cover, and additional securing means complementally formed to the threaded end of the container for detachably mounting and securing the sprayer head on the container comprising circumferentially and vertically spaced indentations corresponding to the pitch of the container thread and the depth of the indentation complemental to root diameter of the threaded container opening whereby the sprayer head is adapted to be detachably connected to the liquid container.

5. The combination with a spray gun including a liquid container for the liquid to be sprayed and a sprayer head including an intermediate wall, of a hose connection adapter, said sprayer head having an inlet opening and said hose connection adapter having one end complementally formed to the inlet opening, and the other end complementally formed to the hose end to which it is adapted to be connected, and securing means for detachably securing the hose connection adapter to the intermediate wall of the sprayer head.

6. As an article of manufacture, a hose connection for a sprayer head of a spray gun including an intermediate wall and provided with an opening to detachably receive the hose connection, said hose connection at one end including securing means complementally formed to position securing means on the sprayer head contiguous to the opening, whereby upon the hose connection being inserted in the opening, the sprayer head, intermediate wall and hose connection are adapted to be detachably secured together by the aforesaid complementally formed securing means.

7. As an article of manufacture, a hose adapter for a sprayer head of a spray gun provided with an opening to detachably receive different hose adapters for adapting the sprayer head for use with hoses having differently shaped hose ends, said hose adapter at one end complementally formed to the opening in the sprayer head, and the hose adapter at the opposite end complementally formed to a conventional hose end to be connected to the sprayer head, the end of the hose adapter adapted for detachably connecting to the sprayer head after insertion through the opening, and securing means for detachably affixing the hose adapter in place extending transversely to the longitudinal axis of the hose adapter and affixed to the sprayer head.

8. A sprayer head comprising a partition member mounted upon a flanged portion of the sprayer head providing an upper chamber and a cap portion adapted for mounting the sprayer head on a container, a hose adapter detachably mounted upon the sprayer head and adapted to extend within the upper chamber, and securing means affixing the hose adapter to the partition member and the partition member to the flanged portion of the sprayer head so that the hose adapter and partition member are detachably affixed to the sprayer head.

9. As an article of manufacture, a foam sprayer attachment for the sprayer head of a spray gun comprising a liquid discharge tube mounted contiguous to a discharge opening in the sprayer head, said foam sprayer attachment comprising a sheet metal cup-shaped member, a tapered tubular ferrule affixed to the cup-shaped member and complementally formed to be attached at the discharge opening of the sprayer head contiguous to the discharge end of the liquid discharge tube to form an annular passageway about the discharge tube, said sheet

metal cup-shaped member formed with an annular groove contiguous to the discharge opening thereof, a series of contiguously positioned foraminated disks detachably positioned in said annular groove, said disks complementally formed to said annular groove and adapted to be deformed so that the disks are adapted to be snapped into and out of said annular groove, and spacing means provided on the faces of certain of said disks so that the disks are adapted to be nested or spaced apart for 5 foaming the liquid, whereby the liquid sprayed and discharged through the contiguously positioned disks in the annular groove under air pressure applied to the spray gun is foamed and sprayed.

10. The combination with a spray head of a spray gun including a detachable hose connection, of a partition member complementally formed to a flanged portion of an inverted cup-shaped member of the spray head dividing the spray head into a chamber and a lower closure for a container upon which the spray head is 15 adapted to be affixed, a liquid tube extending through the partition member and the upper portion thereof within the chamber substantially parallel to the partition member, and an L-shaped tube support member comprising a vertical portion and a transverse portion adapted to support the upper portion of the tube as it extends through an opening provided in the vertical portion upon insertion of the tube through an opening provided in the transverse portion in alignment with an opening provided in the partition member, said support member adapted to abut the lower face of the partition member to extend through and abut the inner face of the cup-shaped member, and said upper end of the support member being deformable for affixing the cup-shaped member and partition member together, and additional securing means for affixing 25 the cup-shaped member, the hose connection and partition means together in assembled relationship but permitting the hose connection to be attached and detached.

11. The combination with a spray head of a spray gun including a detachable hose connection, of a partition 30 member complementally formed to a flanged portion of an inverted cup-shaped member of the spray head dividing the spray head into a chamber and a lower closure for a container upon which the spray head is adapted to be affixed, a liquid tube extending through the partition member and the upper portion substantially parallel to the partition member, a tubular ferrule adapted for receiving the liquid tube and mounted in the partition member and extending therethrough and affixed to said partition member, and the lower portion of said ferrule adapted to be deformed with the liquid tube in place for securing the liquid tube on the partition member, and securing means for detachably securing the hose connection, cup-shaped member and partition member together in assembled relationship but permitting the hose connection to be attached and detached.

12. The combination with a spray head of a spray gun including a detachable hose connection and adapted to be connected to a small-mouthed container, of a partition member complementally formed to a flanged portion of an inverted cup-shaped member of the spray head dividing the spray head into a chamber and a lower closure for a large-mouthed container, said lower closure adapted to abut the upper face of the small-mouthed container and a closure member for the small-mouthed container operatively located on the partition member so that the periphery of the container lies substantially within the closure for the larger mouthed container, and the closure for the small-mouthed container is adapted to extend within the large-mouthed container, and a liquid tube and valve mechanism for the liquid tube operatively positioned on the partition member and extending therethrough for use with the form of container to which the spray head is affixed.

13. The combination with a spray head of a spray gun 75 including a detachable hose connection and adapted to be

connected to a large-mouthed container, of a partition member complementally formed to a flanged portion of an inverted cup-shaped member of the spray head dividing the spray head into a chamber and a lower closure for the large-mouthed container, and a separably formed closure member for a small-mouthed container affixed to the partition member so that the periphery of the container lies substantially within the closure for the larger mouthed container, and the closure for the small-mouthed container is adapted to extend within the large-mouthed container, and a liquid tube and valve mechanism for the liquid tube operatively positioned on the partition member and extending therethrough for use with the form of container to which the spray head is affixed.

14. As an article of manufacture, a partition assembly for a sprayer head of a spray gun having a hose connection, said sprayer head comprising a sprayer cover for the liquid container comprising an upper cylindrical portion provided with a discharge outlet opening and an inlet opening for a spraying fluid under pressure, said inlet opening adapted for detachably mounting the hose connection, said partition assembly comprising a liquid tube, a tubular ferrule adapted to receive the liquid tube, and said ferrule affixed to the partition member and said liquid tube, and means formed on said partition member adapted for detachably affixing the hose connection to the sprayer head.

15. As an article of manufacture, a partition assembly for a sprayer head of a spray gun having a hose connection, said sprayer head comprising a sprayer cover for the liquid container comprising an upper cylindrical portion provided with a discharge outlet opening and an inlet opening for a spraying fluid under pressure, said inlet opening adapted for detachably mounting the hose connection, said partition assembly comprising a liquid tube, a tubular ferrule adapted to receive the liquid tube, a closure member for a small mouthed container, said ferrule member adapted to affix the partition member and closure member together and said liquid tube, and securing means adapted for securing said closure member and partition member together and further adapted for detachably affixing the hose connection to the sprayer head.

16. The combination with a sprayer head of a spray gun comprising a detachable hose connection, a partition member, a liquid tube, and a valve rod for controlling the flow of fluid through the liquid tube of the spray gun, said valve rod extending through the partition member, of a member complementally formed to the upper end of the valve rod extending above the partition member for manipulating and adjusting the valve rod, and a similarly formed member adapted to extend through the hose connection and the sprayer head for affixing the hose connection to the sprayer head, whereby the members are interchangeable.

17. The combination with a foam sprayer attachment for the sprayer head of a sprayer gun, of an elongated securing means for detachably securing together separable members of the sprayer head, said foam sprayer attachment comprising a series of detachably mounted foraminated disks and a hollow ferrule for detachably connecting the foam sprayer attachment to the sprayer

head, said elongated securing means complementally formed to the hollow ferrule, whereby when the elongated securing means is detached from the sprayer head, the elongated securing means is adapted for insertion through the hollow ferrule to detach the foraminated disks from the foam sprayer attachment.

18. The combination with a spray gun comprising a sprayer head including a partition member, of a detachable tubular hose adapter detachably mounted upon the sprayer head, said detachable tubular hose adapter provided with diametrically aligned holes, and securing means operatively mounted with respect to the sprayer head, partition member and hose adapter and extending through said aligned holes of the detachable tubular hose adapter, whereby the aforesaid members are affixed together and the partition member is affixed to the sprayer head.

19. A spray gun adapted for either spraying or foaming and spraying comprising a sprayer head having a hose connection for connecting the spray gun to a source of air under pressure, a liquid discharge tube having its discharge opening contiguous to an outlet opening in the sprayer head forming an annular passage about the liquid discharge tube, and a detachable foam sprayer attachment comprising a sheet metal cup-shaped member formed with an opening and including a tubular bushing affixed within said opening and complementally formed to the outlet opening of the sprayer head for frictionally mounting the tubular bushing of the foam sprayer attachment about the end of the liquid discharge tube, a series of contiguously positioned and deformable foraminous disks for said foam sprayer attachment, and the opposite end of the sheet metal cup-shaped member formed with an annular groove for detachably receiving the series of contiguously positioned and deformable foraminous disks, spacing means provided on the faces of certain of said disks so that the disks are adapted to be nested or spaced apart for foaming the liquid, whereby the liquid is discharged as a foam with the foam sprayer attachment mounted upon the spray head, and with the foam sprayer attachment detached, the spray gun is adapted for spraying.
